UNITED STATES PATENT OFFICE.

SAMUEL SCHUTZ, OF NEW YORK, N. Y.

GLASS-TOP COUNTER FOR STORES.

SPECIFICATION forming part of Letters Patent No. 294,512, dated March 4, 1884.

Application filed September 26, 1883. (No model.)

To all whom it may concern:

Be it known that I, SAMUEL SCHUTZ, of the city, county, and State of New York, have invented a new and useful Improvement in Sales-Counters for Stores; and I do hereby declare that the following is a full and exact description thereof, reference being had to the accompanying drawings, and to the letters of reference marked thereon, making a part of this specification.

My invention relates to an improvement in that class of counters for stores in which the top is fitted with glass. The counters and show-cases of this description, as heretofore constructed, have failed in meeting the demand for an illuminated counter and the wants of the public in this respect, in view of the fact that the upper portion of the counter has been constructed either as a detachable show-case, fitted with drawers, and therefore unsuited to the display therein, or to the handling therefrom of a general stock of goods, and to the furnishing or fitting up of a first-class store, or has been composed of a series of panes of glass, impairing the continuity of surface desirable in the top of the counter, and which, being superimposed upon tiers of two or more drawers, is ill adapted for the purpose of displaying or storing the goods. I may state, therefore, by way of premise, that my invention does not relate to or embrace the combination of a detachable transparent top or show case with a stationary counter, either with or without drawers, nor to a counter whose top surface is composed of a series of panes of glass superimposed above the tiers of drawers, nor to a transparent show-case, as such; but my said invention consists in the combination, with a secure frame adapted to constitute, in neat form, the top edges of a fixed counter, and with a receptacle under the same, consisting of a shelf inclosed by the solid front and ends of the counter, and by hinged panels as the rear, of a single continuous sheet of glass supported by and upon said frame, and intermediate, as required, by slender upright supports springing from the shelf, whereby a continuous, clean, hard, smooth top surface is provided the whole length of the counter, adapted for measuring out and exhibiting

goods without the possibility of injury thereto, and through which the goods stored and protected in the receptacle beneath said top plate may be fully displayed for inspection without removal, except as occasion requires, 55 and be removed and replaced without interference with the full use of the counter in the exhibition and handling of the goods thereon.

In the accompanying drawings, Figure 1 is a front elevation of my improved glass-top counter broken in its length; Fig. 2, a top view thereof; Fig. 3, a rear elevation of one end, and Fig. 4 a transverse section in line *x x* of Fig. 1.

A represents the counter, constructed solidly 65 and neatly in any approved form and style of finish, with its upper portion projecting somewhat at the front in the customary manner.

B is an upper shelf dividing this upper part of the counter from that below it, and which, 70 in connection with the solid ends and sides, forms a neat receptacle, *C*, Fig. 4, for the reception and display of goods, extending the full length and width of the counter, and which is closed at the rear by a series of hinged 75 drop-panels, *C' C'*.

D is a continuous unbroken frame extending around the entire top edge of the counter at front, ends, and rear, making a neat finish thereto, and which is recessed on its inner 80 side to receive and properly support the edges of a continuous sheet of plate-glass, *E*, fitted to rest closely within the recess, and to be firmly and solidly upheld thereby, a narrow packing-strip of rubber being preferably inserted under the glass, to make a better joint and seat for the same.

F *F* are neat slender columns, preferably of glass, resting upon the shelf *B*, and serving as intermediate supports for the continuous extended plate of glass *E*. The edges of the glass plate may be beveled and left to project slightly above the inclosing-frame *D*, or be inserted flush therewith, so that the top of the counter shall be perfectly smooth and unbroken.

The goods-receptacle *C* may be neatly finished in any desirable style, and its sides lined with mirrors, to promote an effective display of the goods placed therein.

I claim as my invention—
An improved stationary sales-counter, constructed with a continuous transparent top of plate-glass, supported upon an extended fixed frame, constituting the edges of the counter, and covering a receptacle in the top of the counter, closed at front and ends by its solid casing and in the rear by suitable drop-panels, all substantially in the manner and to for the purpose herein set forth.

In testimony whereof I have signed my name to this specification in the presence of two subscribing witnesses.

SAMUEL SCHUTZ.
